UNITED STATES PATENT OFFICE.

CHARLES E. NASH, OF SOUTH HADLEY, MASSACHUSETTS.

WHEEL-HOE.

SPECIFICATION forming part of Letters Patent No. 367,835, dated August 9, 1887.

Application filed December 16, 1886. Serial No. 221,756. (No model.)

To all whom it may concern:

Be it known that I, CHARLES E. NASH, of South Hadley, in the county of Hampshire and Commonwealth of Massachusetts, have 5 invented a new and useful Improvement in Wheel-Hoes, of which the following is a specification, reference being had to the accompanying drawings, forming part thereof.

My invention relates to hoes carried between two wheels and drawn by horse-power for destroying weeds and hilling up the soil upon both sides of a row of corn or other crop.

The object of my invention is to improve the construction of these hoes by providing 15 means whereby the blade-carrying beams can be quickly and easily lifted from the ground to clear large stones and other obstructions, and also by providing means whereby the said beams can be conveniently and accurately 20 guided independently of the carriage to follow irregularities in the rows.

To these ends my invention consists in the construction and combination of parts herein-after fully described, and particularly pointed 25 out in the claims.

Referring to the drawings, in which like letters designate like parts throughout, Figure 1 is a perspective view of a wheel-hoe constructed according to my invention. Fig. 2 30 is a side elevation of parts thereof, illustrating the operation of elevating the blade-carrying frame above the ground. Fig. 3 is a plan view with the seat removed to more clearly show the parts beneath the same.

35 The letters A and B designate two diverging beams carrying the blades b, said beams being connected together by the arched braces C D, and said braces in turn being united by a cross-bar, E, secured to each brace at the 40 middle point of the arch. The braces are secured to the beams by bolts passing through slots h in horizontal feet g, with which said braces terminate, thus providing for adjustment of the beams toward and away from each 45 other to suit the particular kind of crop with which the hoe is to be used. The said beams, braces, and cross-bar thus form a frame, which I will designate as the "blade-carrying frame." This frame is supported, in the manner presently described, upon a carriage consisting of the axle N, wheels W, and tongue

50 O, said tongue being united to the axle by the diverging arms P, thus leaving an open space between said arms to enable the driver to observe any irregularities in the row and to accurately guide the frame accordingly, as hereinafter described. A seat, S, is supported upon the axle by standards T, or in any other suitable manner, and the carriage will be provided with the usual draft-bar and whiffletrees 55 (not shown) for attaching horses thereto.

Pivoted upon a bar, G, near the point of intersection of arms P of the tongue, is a lifting-lever consisting of a long arm, V, connected with cross-bar E midway between braces C D 60 by a swivel-joint, F, and a short arm, H, extending upwardly at an obtuse angle to arm V, as shown, and terminating in a suitable foot-rest. By means of this lever the driver, by pressing down the short arm with one foot, can 65 elevate the frame more or less, as may be necessary, to clear large stones and other obstructions, such operation being indicated by the dotted lines in Fig. 2. A hook, R, is pivoted to the tongue in position to grasp the short 70 arm of the lever when the frame is elevated to its highest point and retain it in that position when driving to and from the field.

A vertical steering-lever, J, having the lateral arm K at its lower end, is journaled in 75 the tongue, so as to have free axial movement, said steering-lever being located in front of the lifting-lever just described, but within easy reach of the driver's foot, and being provided with a foot-bar, I. The lateral arm K is connected with an eye, M, upon beam A by a link, L. From this construction and arrangement it is obvious that by keeping one foot upon foot-bar I the driver can accurately guide 80 the frame independently of the carriage, the 85 swivel-joint F permitting the former to turn laterally to follow such guiding movement.

The draft-strain of the blade-carrying frame will be borne principally by the steering-lever and its connecting-link, the swivel-joint F 90 serving to steady the movement of said frame.

The operation of the hoe thus constructed has been indicated in the above description.

The beams A B are adjusted laterally by means of the bolts and slots h to correspond 95 with the particular crop with which the hoe is to be used—potatoes, for instance, requir-

ing a greater space between the beams than corn. The hoe is then started at the end of a row with one beam upon each side thereof, or, in other words, straddling the same.

5 It is not customary or desirable to use wheel-hoes with corn after the latter has reached a height of more than two and one-half or three feet, and wheels of the ordinary size will permit crops of that height to pass beneath the axle without being broken. The blades *b* will draw the soil closely about the base of the standing crop upon both sides of the row, and will also effectually destroy the weeds to a distance each side thereof equal to 10 the distance between the rear ends of the beams A B. The driver with one foot upon the rest at the end of arm H is enabled to easily and quickly operate the lever H V to elevate the frame above the ground to clear large stones 15 and other obstructions that would be liable to clog between the beams or injure the blades. Moreover, in crops planted by hand especially, many of the hills will be found to be out of alignment with the others, and by keeping 20 his other foot upon foot-bar I the driver is enabled to conveniently and accurately guide the beams A B through steering-lever J and link L upon each side of such irregular hills, which would otherwise be uprooted and destroyed. The blades *b* will be detachably secured to the beams in the usual manner, so that 25 blades of different sizes and contour can be used with different crops and with the various stages in the growth thereof.

It is obvious that I could secure a hand-bar 35 to the steering-lever, so as to guide the frame with one hand, instead of with the foot; but I prefer the construction shown.

It is also obvious that other modifications could be made within the spirit of my invention. 40

I claim—

1. In a wheel-hoe, the combination, with a blade-carrying frame consisting of two diverging beams adjustably connected together by 45 two arched braces projecting upwardly upon opposite sides of the axle of the carriage and a cross-bar uniting said braces above the axle, of a swivel-joint connecting said frame with the carriage, and means, substantially as described, 50 for both elevating and laterally turning said frame independently of the carriage.

2. In a wheel-hoe, the combination, with the carriage having the tongue connected thereto by the diverging arms P, of the blade-carrying frame constructed substantially as described, and suspended from said carriage by a swivel-joint in such manner as to cause its front end to extend in front of the axle, the steering-lever J, having the lateral arm K at 55 its lower end and foot-bar I at its upper end, and link L, connecting said arm K with said frame, substantially in the manner and for the purpose set forth.

CHARLES E. NASH.
